LIMIT STOP MECHANISM FOR POWER-OPERATED GUN MOUNTS

Paul E. Humphrey, San Diego, Calif., assignor to the United States of America as represented by the Secretary of War

Application January 30, 1947, Serial No. 725,194

7 Claims. (Cl. 89—41)

1

The invention described herein may be manufactured and used by or for the Government for governmental purposes without payment to me of any royalty thereon.

This invention relates to contour followers and has special reference to the application of a device of this kind to an aircraft gun mount.

Gun mounts to which this device is applicable are usually rotatable in azimuth for the full three hundred sixty degrees and in elevation from slightly below the horizontal to substantially vertical, i. e., from several degrees downfire to ninety degrees upfire.

There are, however, some positions in azimuth in which the guns could not be fired, if pointed lower than several degrees upfire, without striking vulnerable parts of the craft upon which they are mounted. In certain military aircraft, for instance, the guns, when pointed aft, could not be trained much lower than six degrees upfire before the line of fire would pass through the upper gunner's sighting station.

It is therefore a principal object of this invention to provide mechanism which will limit to a safe angle the declination of the line of fire of the guns in any azimuth position.

More specifically stated, an object is to provide a mechanical limiting means for arresting gun declination together with means to move said limiting means to different positions as a result of changing the line of fire in azimuth.

An additional object of the invention is to provide a device which is adapted to interrupt the power circuit by which the guns are being moved in declination as well as the firing circuit whenever the guns are trained so that the firing line passes through any portion of the craft upon which the device is being used.

Another object is to provide means to mechanically disconnect the power means which operates the gun elevating means coincidentally with the breaking of the power circuit and the firing circuit.

Another object is to provide means to cushion the inertia forces of the guns when they strike the azimuth adjusted stop which determines the limit of declination of the line of fire.

Other objects and advantages will be evident upon consideration of the following description when read with reference to the drawings, wherein the single figure of the drawing is a schematic view in perspective of an embodiment of my invention.

Referring to the drawing, a horizontally disposed ring gear 10 is nonrotatably carried by 55

the turret supporting frame (not shown), and has internal teeth 12 which may preferably extend completely around the inside of the ring.

A reversible motor 11 is carried by the revolvable turret and has a pinion 13 in mesh with the teeth 12, whereby rotation of the motor 11 revolves the turret in azimuth. Motor 11 is operable in either direction by a means which, for purposes of illustration only, is herein shown as 10 a double-throw switch 17.

A vertically disposed ring 14 also carried by the revolving turret has a toothed gear segment 16 which needs extend only part way around the ring. Rotation of the ring 14 in one or the other 15 direction points the guns 15 on the turret at an upward or a downward angle as required.

A reversible motor 18 is provided to rotate the ring 14 by means of a pinion 20, idler 22, gear 24, shaft 26, and gear 28. Motor 18 is operable in 20 either direction by a means which, for purposes of illustration only, is herein shown as a double-throw switch 30.

The motors 11 and 18 and their circuits, the ring gears 10 and 14 and connecting gears 13, 20, 22, 25 24 and 28 are schematic representations of the structures in conventional use on aircraft gun turrets and are the parts which must be used in combination with my invention to achieve the objects set forth.

30 The ring 14 is shown in the position which it assumes when the guns are pointed at approximately five degrees upfire. When the guns are pointed substantially in a vertical direction, the upper end of the gear segment 16 will be located 35 in the position shown by the dotted line 32.

A pinion 34 at the lower end of a vertical shaft 36 engages the teeth 12 of the ring gear 10. The upper end of the shaft is provided with a bevel pinion 38 which is in mesh with a bevel gear 40 carried on the outer end of the horizontally extending shaft 42. A pinion 44 fast on the rear end of the shaft 42 meshes with three idler pinions 46 which in turn mesh with the internal ring gear 48. Pinions 46 rotate on studs 50 which 45 are fast on a nonrotatable front cover plate which may be part of the casing within which the gear set is housed. The nonrotatable front cover plate which carries the studs 50 has been removed to show the gear set more clearly.

50 The ring gear 48 is fast on the forward end of a shaft 52, the rearward end of this shaft being provided with a cam 54 which is adapted to engage a roller 56 which is pivotally supported in a slot 58 in lever 60 by a pin 62. The cam 54 thus forms a fulcrum of adjustable height upon

which the lever 60 may rock, the height of the fulcrum depending on the position in azimuth to which the turret has been turned with respect to the nonrotatable ring gear 10. The upper or power end of the lever is slotted clevis fashion at 64 for the rod end 66 which is hingedly connected to the lever by the pin 68. The rod 70 which carries the rod end 66 at one end carries a clevis 72 at the other. The limbs of the clevis 72 are relatively far apart so that the gear segment 16 may pass freely between the limbs when the end of the segment moves from a lower position, as for instance the position 32, to the position shown in the drawing.

The upper end of the segment 16 is provided transversely with a half round groove 74 which engages the clevis pin 76, which is fast in the clevis 72, when the segment is near the end of its travel in the direction of the arrow 78. The clevis pin 76 is prolonged rearwardly beyond the clevis as at 80 so as to be supported in an arcuate slot 82 formed in a guide member 84 which may be a part of the turret frame (not shown) or may be attached thereto. The pin extension 80 and slot 82 maintain the clevis 72 always in a position for re-engagement by the segment 16 when the end of the segment 16 retires from the position shown in the drawing to the position 32 or to some position intermediate the position 32 and the position shown.

The lower or work end of the lever 60, like the upper end, is slotted clevis fashion as at 86 to allow the rod 88 to pass freely through the slot. A hinge pin 90 passes through the clevis limbs and through the rod 88. The rod 88 is slidably axially in bearings 92 and 94 carried by the turret frame. A relatively heavy compression spring 95 is interposed between the lower end of the lever 60 and the bearing 94. A head 96 may be provided on the rod 88 to limit its travel in the direction of the arrow 98, or the head 96 may be omitted and the spring 95 itself will act as a stop when compressed to the extent that the coils contact each other.

An arm 100 is pinned to the rod 88 so as to move with the rod when the rod moves axially, the outer end of the arm being provided with an opening for slidably receiving the rod 102. A collar 104 is fast on the rear end of the rod 102 and a cushioning spring 106 is held under slight compression between the collar and the arm 100.

The forward end of the rod 102 carries a clevis 108 between the sides of which the power end of a lever 110 is hinged by a pin 112, the work end of the lever 110 being adapted to operate the push rod 114 of a relay 116, whereby the firing circuit 118 and the circuit 120, which controls the operation of the motor 18 in one direction of rotation, may be interrupted.

The lever 110 is pinned to the vertical shaft 122 upon which it fulcrums, whereby operation of the lever 110 by axial movement of the rod 102 in the direction of the arrow 98 rocks the shaft through a relatively small angle. A clutch shifting fork 124 fast on the upper end of the shaft 122 is provided for operating a friction clutch 126 which, when disengaged, prevents rotation of the shaft 26 by the motor 18. A battery 128 supplies the current for the several circuits. A switch 130 operates a relay 132 for closing the firing circuit. It should be kept in mind that the entire mechanism shown in the drawing is mounted on and revolves with the turret except the ring gear 10 which is nonrotative.

It is noted that the electric circuits with their switches and relays are merely schematic; for instance, the manual switches 17 and 30, for controlling rotation of the motors 11 and 18 are usually, in actual practice, replaced by automatic controls operated by the sighting mechanism.

The drawing shows the condition which the device assumes when the guns are pointed directly aft and the line of fire is adjusted to about five degrees upfire which is the low limit for this azimuth position necessary to avoid firing through the upper gunner's sighting station.

For illustrative purposes it may be assumed that the guns, both in azimuth and in elevation, are pointed in some other direction than the direction shown. The procedure to accomplish the condition shown in the drawing is substantially as follows:

The motor 11 is rotated until the turret and the entire mechanism herein disclosed, except the ring gear 10 which is nonrotatable, is rotated to the position of the drawing. In so rotating the mechanism, the pinion 34 rolls in the teeth 12 of the ring 10, thereby turning the shaft 36, bevel gears 38 and 40, pinion 44, idlers 46, ring 48, shaft 52 and cam 54. When the guns point directly aft, the cam will be in the position shown, i. e., with the highest point on the roller 56. Thereafter, or simultaneously with this azimuth rotation, the motor 18 is actuated and gear segment 16 rotated in the direction of the arrow 78 to bring the guns down and the end 32 of the segment 16 up until the half round groove 74 engages the clevis pin 76 and carries it forward, pulling the rod 70 with it in the direction of the arrow 134, thus rocking the lever 60 on its fulcrum, which, in this azimuth position, is the high point on the cam 54. The upper end of the lever 60 will continue to move in the direction of the arrow 134 until the head 96 of the rod 88 strikes the bearing 92 or until the spring 95 comes solid. At this stage the pin 90 may be considered the fulcrum; the pin 68, the point of application of the force; and the cam 54, the adjustable stop which limits rotary movement of the segment 16, and consequently, limits gun declination. Obviously, any stop which is automatically adjustable to vary gun declination as a function of turret rotation in azimuth will be considered within the scope of the invention.

It is noted that while further downward tilting of the guns is always prevented when the head 96 strikes the bearing 92 or when the spring 95 comes solid, the point at which this takes place depends on how high a fulcrum is being provided by the cam 54 and this depends on the position of the turret in azimuth, i. e., if the turret had been turned until the guns had pointed forward, the low instead of the high side of the cam 54 would have provided the fulcrum and the rod 70 would have moved farther in the direction of the arrow 134, whereby the guns may have stopped their downward tilting movement at five degrees downfire as seen at 136 instead of six degrees upfire as seen at 15.

Movement of the rod 88 to its "stop" position simultaneously moved the arm 100, rod 102 and the lever 110 thereby to operate the relay 116 and thereby break the relay circuit 118 which disconnected the firing circuit, operation of the relay at the same time disconnecting that side of the circuit of the motor 18 which moved the guns in declination. The same move-

ment of the rod 88 in the direction of the arrow 98 also operated the rod 102, clevis 108, lever 110, shaft 122 and fork 124 which drivably disconnected the motor 18 from the segment 16 by disengaging the clutch 126 to prevent motor inertia from forcing the rod 88 too tightly against its stop 96 and from packing the coils of the spring 95 too tightly together if the spring is being used as a stop. If the relay 116 becomes fully operated before the head 96 reaches the bearing 92, the spring 102 will yield and allow the rod 88 to move further until the head 96 is seated.

While in the exemplification of the invention herein disclosed, the electric circuits are broken and the motor unclutched coincidentally with the mechanical arresting of gun declination as a function of gun movement in azimuth, any device will be considered within the scope of this invention whether the electric circuits are thus broken or not and whether the motor is thus unclutched or not.

In the embodiment of the invention herein disclosed, the cam 54 has a single high point which limits down tilt of the guns to the position 15 only when the guns are pointed directly aft. It will be apparent, that additional raised fulcrum points may be spaced around the cam to limit downward tilt of the guns in other than the aft position. The contour of the cam thus delineates the contour of the line of fire of the guns.

Having thus described an embodiment of my invention, I claim:

1. In a device for controlling an aircraft gun turret of the class having electric power means for moving the guns in elevation or declination, means for moving the guns in azimuth, and stop means for limiting gun movement in declination as a function of turret rotation in azimuth, the improvement in stop means which comprises a cam carried on said turret, gearing carried on said turret operative by movement of said turret in azimuth to rotate said cam, a lever of the first class fulcrumed on said cam, means on the power end of said lever engageable by the means for moving the gun in declination, a stop for the work end of said lever, and means connected to the work end of said lever operative by movement of the power end to disconnect the electric circuit of the power means when said work end means is moving into contact with said stop.

2. The combination in an aircraft gun turret of the type having an electric motor and an electric motor operated means for moving the guns in elevation or declination, means for moving the guns in azimuth, and stop means for limiting gun movement in declination as a function of turret rotation in azimuth, the improvement in stop means which comprises a cam carried on said turret, gearing carried on said turret operative by movement of said turret in azimuth to rotate said cam, a lever of the first class having its fulcrum on the working surface of said cam, linkage connecting the power end of said lever to said electric power operated means whereby movement of said guns in declination rocks said lever on said fulcrum, a stop for the work end of said lever, and means operative by movement of said work end to said stop to mechanically disconnect said electric motor from said electric motor operated means and to electrically break the circuit to said motor.

3. For use in connection with an aircraft gun turret of the type which includes an electric motor,

electric motor operated means for moving the guns in elevation or in declination, a second electric motor for moving the guns in azimuth, and stop means for limiting gun movement in declination as a function of turret rotation in azimuth, the improvement in stop means which comprises a rotatable cam carried by said turret, gearing carried by said turret operative by movement of said turret in azimuth to rotate said cam, a lever of the first class having fulcrum on the working surface of said cam, linkage connecting the power end of said lever to said electric motor operated means whereby movement of said guns in declination rocks said lever on said fulcrum, a stop for the work end of said lever, a relay normally completing the first said motor circuit and a firing circuit, and means operative by movement of the work end of said lever to said stop to mechanically disconnect the first said electric motor from said electric motor operated means and to operate said relay to break the circuit to the first said motor and to the firing circuit.

4. For use in connection with an aircraft gun turret of the type in which the guns may be moved in elevation or declination, or in azimuth, said type including stop means for limiting gun movement in declination as a function of turret rotation in azimuth, an electric motor having two circuits for rotation in opposite directions, a firing circuit, electric motor operated means operable by said electric motor in one or the other direction for moving the gun in elevation or in declination, and a second electric motor for moving the gun in azimuth, the improvement which comprises a rotatable cam carried by the turret, gearing carried by said turret operable by movement of said turret by said second electric motor in either direction in azimuth to rotate said cam, a lever of the first order adapted to fulcrum on some part of the working surface of said cam depending on the azimuth position of said turret, linkage connecting the power end of said lever to said electric motor operated means whereby movement of said guns in declination rocks said lever on said fulcrum, a rod joined to the work end of said lever, a spring-cushioned stop for arresting movement of said rod to thereby limit declination of said gun, clutch means operable by movement of said rod to disengage the first said motor from said electric motor operable means, and switch means operable by movement of said rod to open the firing circuit and to open that circuit of the first said electric motor which rocks the guns in declination.

5. In a device for controlling an aircraft gun turret of the class which includes means rotatable for moving the gun in declination, means rotatable for moving the gun in azimuth, and means to arrest gun movement at a predetermined degree of declination when the gun is positioned at a predetermined point in azimuth, the improvement in arresting means which comprises a lever, connecting linkage joining the means rotatable for moving the gun in declination to the power end of said lever, an arresting member operatively joined to the work end of said lever, a fixed mechanical stop associated with said arresting member for arresting movement of said arresting member at the extreme end of its travel, a cam adjacent said lever intermediate its power and work ends, fulcrum points of different predetermined heights for said lever around the periphery of said cam, and power transmitting means connecting said cam for rotation by said means rotatable for moving the gun in azimuth,

6. The device of claim 5 with power means for rotating the means rotatable for moving the gun in declination, power transmitting means drivably connecting the power means to the means rotatable for moving the gun in declination, a clutch joining several parts of said power transmitting means, a clutch disengaging arm, and motion transmitting means including a lever for joining said arresting member to said arm so constructed that movement of said arresting member to said fixed mechanical stop disengages said clutch.

7. The device of claim 6 with an electric switch associated with said lever and operable by said lever to the open position upon movement of said 15 arresting member to the fixed mechanical stop.
